UNITED STATES PATENT OFFICE.

CALVIN JACKSON, OF JACKSONWALD, PENNSYLVANIA.

BALLOT-BOX.

SPECIFICATION forming part of Letters Patent No. 448,524, dated March 17, 1891.

Application filed May 28, 1890. Serial No. 353,425. (No model.)

To all whom it may concern:

Be it known that I, CALVIN JACKSON, of Jacksonwald, in the county of Berks and State of Pennsylvania, have invented a new and 5 Improved Ballot-Box, of which the following is a full, clear, and exact description.

The object of the invention is to provide a simple and efficient means for balloting in secret, especially for the use of clubs, societies, 10 lodges, &c.

The box includes, primarily, two compartments, one for containing the bulk of the ballots and the other a receiving-compartment for the ballots cast, communication between 15 the two being controlled by a transfer mechanism, which is so constructed and arranged as to transfer the ballots in a single succession from the main compartment to the receiving-compartment.

20 The invention also comprises various details of construction, all as will be hereinafter described, and pointed out in the claims.

Reference is to be had to the accompanying drawings, forming a part of this specification, 25 in which similar figures of reference indicate corresponding parts in all the views.

Figure 1 is a vertical sectional elevation of a ballot-box embodying my invention, the section being on the irregular line $x x$ of Fig. 3. 30 Fig. 2 is a like view on the line $y y$ of Fig. 3. Fig. 3 is a plan view partly broken away and in section. Fig. 4 is a perspective view of one set of the transfer devices and the box-partitions removed from the box, the bottom of the 35 latter being indicated by dotted lines. Fig. 5 is a detail side view illustrating the position of the transfer-disk when a ballot leaves it to pass to the receiving or recording department.

Fig. 6 is a like view in reverse position, which 40 is its normal position. Figs. 7 and 8 are side views of the transfer-disk and the stop employed in connection therewith from the reverse side to that shown in Figs. 5 and 6, Fig. 7 representing the disk in such a position 45 with respect to the stop and escape-aperture for the ballots that a ballot cannot escape from the pocket of the disk, nor can one enter the said pocket, and Fig. 8 illustrating the disk in position of having allowed the ballot 50 to escape, in which latter position the ballots are cut off from the escape-aperture, the location of the latter being indicated by a dot-

ted line in both figures. Fig. 9 is a vertical sectional elevation of the lower portion of the box in an inverted position. Fig. 10 is a 55 broken sectional plan view on the line $z z$ of Fig. 2, the body of the box being omitted; and Figs. 11, 12, and 13 illustrate a modification in which the operating-rod of the disk acts in conjunction with the latter for effecting 60 the transfer of the balls without a separate stop, and which will be hereinafter more particularly referred to. Fig. 14 is a plan view of one of the transfer-disks and its stop.

In the preferred embodiment of my invention the main and receiving compartments are arranged in the same vertical plane, and the ballots are in the form of balls, which are brought into such a position by a rotary reciprocating disk as to fall by their own gravity 70 in a single succession into the receiving-compartment, the compartments and the operating mechanism being in duplicate. In this preferred construction the box or casing 10, of any preferred size and external form, is 75 provided with a cover 11, secured thereon by screws 12 or by other suitable means, so as to be removed when required for repairing the mechanism, but which cover is practically permanent. The box 10 is divided into two 80 upper main compartments 13 13 and two lower receiving-compartments 14 14 in the bottom of the box or case 10, the said box between the upper and lower compartments being circularly bored, as at 10°. The vertical partition 15, which separates the two upper compartments 13, is formed with an extension or plug 16, which extends downward into bore 10° to near the two lower compartments, and, with additional plug 16^a, separates the two former 90 compartments from the two latter. The plugs 16 and 16^a are formed with two vertical ducts or passages 17, which extend from the lower compartment 14 to a point above the bottoms of the upper compartments, each being in 95 communication with one of the latter through a lateral aperture 17^a, which form the upper ends of said passages, and each of said passages is also entered from its corresponding main compartment below the apertures 17^a 100 through other transverse apertures 17^b, through which latter apertures the ballots enter in single succession, as presently explained. The two lower or receiving compartments are

separated by a vertical partition 18, and the bottom or cover 19 of said compartments is preferably of glass for the ready observance of the balls therein.

5 In the bottom of each main compartment 13 is fitted a block 20, the upper surface of which curves downwardly and inwardly, in order that the balls will gravitate to the inner side thereof. In the inner side of each block 20 are formed recesses 21, in which recesses the transfer-disks 22 are fitted, the journals 23 of said disks having bearings in the blocks 20 and in the vertical partition 15, and to each disk is connected the lower end 15 of an operating-rod 24, which rods extend upward, passing through the apertured guide-plate 25, secured to the top of partition 15, and to or into apertures 11^a in cover 11, and are provided on their top with push-buttons 24^a.

In order that the particular button pressed by a voter may not be observed by bystanders the cover 11 is provided with a neck or collar 11^b, which is divided by a vertical partition 11^c, and in practice the collar will be of such a height as to make it impossible for a voter to press both buttons simultaneously or by a single insertion of the hand into the collar. A spring 26 on each rod 24 serves to 30 return the same to its normal position after each downward movement, the upper ends of the springs bearing against the underside of the plate 25.

Referring again to the transfer-disks, I will 35 now particularly describe their construction and operation in the preferred form, and as both disks are exactly alike it will suffice to make the description in the singular. The disk 22 is formed at one side with an extension or portion 22^a of greater radius than the main portion of the disk. In the periphery of the disk adjacent to the extension 22^a a pocket 22^b is formed, the said pocket being of double-curve form, as shown, and extending 40 from the extension 22^a to the point 22^c, which point has a slight inward curve on its exterior surface also, the end of the pocket adjacent to point 22^c being in the form of or approximating a small semicircle. The bottom of the pocket also inclines or deepens 45 slightly transversely for a short distance, beginning at the point 22^b, the opposite end of the pocket or end adjacent to extension 22^a extending in a direct transverse line and not inclined. The disk is divided or formed with 50 a peripheral groove 22^d, which extends through the extension 22^a, as seen in Figs. 2 and 4, and partly through the main body of the disk, as indicated in Figs. 5 to 8, and into 55 this peripheral groove 22^d projects a stop 27, that is fixedly secured to the vertical partition 15 of the box, the operation of the disk in connection with the stop, which will be best understood from Figs. 7 and 8, being as follows: The stop is located opposite the escape-aperture 17^b, which leads to duct 17; but the 60 stop projects only partially across said aper-

ture, and its lower inner corner is concaved, as at 27^a. The position of the stop 27 with respect to the pocket of the disk and to the escape-aperture 17^a is such that when the said disk is moved to bring its pocket 22^b coincident with the escape-aperture 17^b the entrance to the pocket is cut off by the near approach of the point 22^c of the disk to the said stop, and when the disk is moved sufficiently to allow entrance of a ballot to the pocket 22^b the inner face of the disk closes or partially closes the said aperture, so that at no time can a ballot pass uninterruptedly 80 through the pocket and escape at said aperture. In Fig. 7 are shown two ballots A A, one in the pocket ready to be brought to the escape-aperture and one at the entrance to the pocket. Before the ballot in the pocket can enter the escape-aperture the disk must be moved to the position in which it appears in Fig. 8, or nearly so, and as it is evident that even the slightest movement of the disk toward the stop narrows the entrance to the 90 pocket, no ballot can enter the latter until the return movement of the disk, which latter movement closes the escape-aperture.

The ballots pass through the escape-aperture 17^b into the duct 17, and from the latter 95 into the lower receiving-compartment 14, corresponding to the main compartment 13, from which the ballot was delivered. When the balloting is closed, the box is bodily inverted, whereupon the ballots in the respective receiving-compartments may be observed and counted through transparent cover 19.

To prevent the return of the ballots into the vertical passages 17 when the box is inverted, the lower ends of said passages are 105 provided with a double check-valve or butterfly-valve 28, one leaf of which is located in each compartment 14, the two leaves being hinged to a pin 29, passing through the plug 16^a. The valve 28 is supported in the closed 110 position when the box is inverted by the flat end 30^a of a rod 30, the said rod extending upward through the partitions and cover of the box to the top of the latter, where it is provided with a button 30^b or similar device 115 to enable a person to grasp it with the fingers. The box being in the inverted position, as in Fig. 9, upon pulling on the rod 30 the flattened end 30^a thereof is drawn downward 120 away from the valve 28, allowing the latter to fall, as indicated by dotted lines, whereupon the ballots in the compartments 14 14 will pass downward into passages 17 and out through ends 17^a thereof into the corresponding compartment 13. A spring 31 on the 125 valve-rod 30 returns it to the normal position upon the button 30^b being released.

The transverse apertures or upper ends 17^a of passages 17 are normally closed by a slide 32, carried by the valve-rod 30 and working 130 in a slit 15^a in partition 15, the said slide being bent twice at right angles in opposite directions to lie over each aperture 17^a. As the rod 30 is pulled to allow the valve 28 to fall,

the slide 32 is drawn away from the apertures 17^a, to be returned thereto upon the release of said rod, whereby the said apertures will be open only when the ballots are being re-
5 turned to the main compartments.

In the modification of the transfer mechanism illustrated in Figs. 11, 12, and 13 the transfer-disks 22 are the same as in the other figures; but in the modification the lower end 10 of the operating-rod 24 is formed with a slight curve and with a slight inwardly-projecting point 33 at the upper end of the curve, and the operating-rod is connected to the disk within the peripheral groove 22^d thereof.

15 In operation when the rod 24 is depressed the pocket 22^b is brought toward the said rod, while the projection 33 on said rod, by reason of the curved form of the latter, is caused by the descent of the rod to approach the pocket 20 22^b of the disk, the arrangement being such that before the pocket is brought coincident with the apertures 17^b the projection 33 of the operating-rod will cut off the entrance to said pocket in substantially the same manner as is done by the separate stop 27.

It will be seen that with a ballot-box of my improved construction the ballots may be preserved as cast until the poll is settled and may be counted without removing them from 30 the box, which makes impossible the manipulation of the vote, which is possible where the ballots are removed for counting; also, as the balloting is strictly secret as to the nature of the ballot cast, members of societies, &c., 35 will by its use be enabled to "black-ball" objectionable candidates for admission without having their action in so doing paraded. The box may also be employed with advantage in voting on resolutions, the election of 40 officers, and for all like purposes.

Having thus described my invention, what I claim as new, and desire to secure by Letters Patent, is—

1. The combination, in a ballot-box having 45 two compartments, one below the other and communicating with each other, of a rotary reciprocating transfer-disk in the bottom of the upper compartment, and a spring-actuated rod secured to one side of the disk and 50 extending up through the compartment, substantially as described.

2. The combination, in a ballot-box having an upper and a lower compartment, and ducts establishing communication between the 55 same, of a transfer-disk controlling the transfer of the ballots from the upper to the lower compartment, and a valve in the latter, substantially as described.

3. The combination, in a ballot-box having 60 an upper and a lower compartment and with

a duct or passage in communication with both, the said passage being in communication with the upper compartment through two apertures, of a transfer-disk located at one aperture, and means, substantially as described, 65 for operating the same, a slide at the other aperture, and an operating-rod for said slide, substantially as described.

4. The combination, in a ballot-box having a main and a receiving compartment and a 70 valve in the latter, of a transfer-disk for controlling the escape of the ballots from the main compartment, a stop adjacent to said disk, and means, substantially as described, for operating said valve and disk, substantially as described.

5. The combination, in a ballot-box having two compartments in communication with each other, of a transfer-disk having an extension and provided in its periphery adjacent to the extension with a pocket of semi-circular form, the bottom of the pocket inclining transversely at the bottom for a portion of its length, and means for operating the disk, substantially as described. 80

6. The combination, in a ballot-box formed with two main compartments and two receiving-compartments and with a raised neck or collar having a vertical partition, of a transfer-disk in each main compartment and an 90 operating-rod therefor, the said operating-rods extending, respectively, into the two compartments of the neck or collar, substantially as described.

7. The ballot-box provided with duplicate 95 main compartments, duplicate receiving-compartments, and mechanism, substantially as described, for transferring the ballots from the former to the latter, the said latter compartments having a transparent cover, substantially as described.

8. The combination, in a ballot-box provided with a main compartment and a receiving-compartment, of a transfer-disk 22, formed with extension 22^a, pocket 22^b, point 105 22^c, and peripheral groove 22^d, and means, substantially as described, for operating said disk.

9. The combination, in a ballot-box provided with upper compartments 13 13 and 110 lower compartments 14 14 and the passages 17 17 and apertures 17^a 17^b, of transfer-disks 22, operating-rods 24 therefor, valve 28, rod 30, and slide 32, substantially as shown and described.
